UNITED STATES PATENT OFFICE.

JOHN M. BURNHAM AND HERMAN J. SCHNEIDER, OF ADAMS, NEBRASKA.

BRAID-CABINET.

1,106,543.

Specification of Letters Patent.

Patented Aug. 11, 1914.

Application filed December 10, 1913. Serial No. 805,787.

To all whom it may concern:

Be it known that we, JOHN M. BURNHAM and HERMAN J. SCHNEIDER, citizens of the United States, residing at Adams, in the county of Gage and State of Nebraska, have invented certain new and useful Improvements in Braid-Cabinets, of which the following is a specification.

The present invention relates in general to store furniture, and more particularly to a novel form of cabinet which is especially designed for the display of various kinds of braid, the object of the invention being to provide a cabinet of this character which has a large capacity for its size and displays all of the braid in an effective manner, thereby eliminating unnecessary handling of the braid, and at the same time protecting the same from accumulations of dust and dirt.

A further object of the invention is to provide a braid cabinet which will hold a large quantity of braid and display the same in an effective manner, which admits of any desired bolt of the braid being removed without displacing the remaining bolts of braid, which can be readily adjusted to receive various widths of braid, and which can be quickly and thoroughly cleaned when desired.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a perspective view of a braid cabinet constructed in accordance with the invention. Fig. 2 is a longitudinal sectional view through the same. Fig. 3 is a transverse sectional view on the line 3—3 of Fig. 2. Fig. 4 is a detail view of one of the stepped tray supports. Fig. 5 is a plan view of one of the blanks from which the partitions are formed. Fig. 6 is a detail view of one of the partitions in its complete form. Fig. 7 is a detail view of one of the trays, having a partition mounted therein.

Corresponding and like parts are referred to in the following description and indicated in all the views of the drawings by the same reference characters.

Referring to the drawings, which illustrate a preferred embodiment of the invention, the numerals 1 designate the sides of the casing, the numeral 2 the front thereof, the numeral 3 the back thereof, and the numeral 4 the bottom thereof. The sides 1 have the upper edges thereof inclined downwardly and forwardly and the front 2 is accordingly much lower than the back 3. This casing includes an upper display compartment A, and a lower compartment which is divided by a transverse partition 5 into a rear storage chamber B and a forward drawer receiving chamber C.

The upper portions of the sides 1 may be formed of frames 1^a having the general shape of a parallelogram and receiving panes of glass 6 or other transparent material. In a similar manner the upper portion of the front 2 is provided with an opening to receive a pane of glass 7 or transparent material, the lower portion of the front being formed with an opening within which a drawer 8 is slidably mounted. The back 3 is provided upon its inner face and at the top thereof with a reflecting surface or mirror 9, and at the bottom with an opening for the storage chamber B, said opening being normally closed by a door 10.

The top 11 has the rear edge thereof hinged at 12 to a strip 13 at the back of the casing. This top is in the form of a frame having a pane of glass 14 fitted therein, and normally rests upon the upper edges of the sides 1 when in a closed position so as to exclude dust and dirt from the casing, although the braid within the display compartment A can be readily seen through the transparent glass panels in the sides, front and top of the casing. The usual form of hinged brace 13^a may be applied to the top 11 so as to maintain the same in a raised position when the cabinet has been opened to obtain access to the braid within the display compartment A.

Secured to the inner faces of the sides 1 at the bottom thereof are correspondingly stepped tray supports 14^a, the general inclination of the stepped upper edges of the tray supports corresponding to the inclination of the upper edges of the sides 1. A series of transversely disposed trays 15 rest loosely upon the corresponding steps of the tray supports 14^a so as to provide a continuous bottom for the display compartment A, the forward edges of the upper

- trays 15 projecting over the rear sides of the lower trays. Each of these trays 15 may be provided with one or more adjustable partitions 16 which are positioned within the tray to subdivide the same according to the widths of the bolts of braid to be supported. As indicated in Fig. 1, the bolts D of braid are held in a substantially upright position, the lower ends thereof resting upon the trays 15 and being received within corresponding sub-divisions thereof provided by the adjustable partitions 16. Owing to the fact that the various braid supporting trays 15 have a stepped arrangement and are arranged successively at higher levels from the front to the rear of the cabinet, the upper ends of the various pieces of braid will be clearly displayed through the glass top of the cabinet so that a prospective purchaser can readily select the kind of braid desired. Any surplus stock may be placed in the storage chamber B, while the drawer 8 which is mounted upon suitable guides 17 may be conveniently utilized to receive various articles, such as pins, scissors, a tape measure, or the like.
- The adjustable partitions for the trays may each be formed from a single blank of sheet material, the edges at the top and ends of the blank being returned at 16^a to stiffen and reinforce the same, while the lower portion of the blank is formed with an extension having an intermediate slit 16^b therein, the portions 16^c of the extension on each side of the slit 16^b being bent in opposite directions to provide the laterally projecting basal flanges. The ends of the partitions frictionally engage the sides of the trays 15, while the basal flanges 16^c rest upon the bottom of the tray so as to retain the partitions in an upright position. It will thus be obvious that these partitions 16 can be quickly positioned within the trays in order to subdivide the same in the manner required by the various widths of braid, and that after once being positioned they are retained firmly in place. This is an important feature of the invention, since as the stock of braid is changed, the partitions 16 within the various trays must always be adjusted and properly positioned to receive the new braid which it is desired to display.
- Having thus described the invention, what we claim as new and desire to secure by Letters Patent, is:—
1. A braid cabinet including a casing having sides which are inclined upwardly from the front to the rear thereof, a removable cover normally closing the top of the casing, a thickness of material applied to the inner face of each side of the casing and having the upper edge thereof stepped to provide a series of tray supporting surfaces, and a series of removable trays extending transversely across the casing and resting upon corresponding tray supporting surfaces of the steps, the depth of each tray corresponding to the height of the steps so that the trays when assembled have a stepped relation to each other, and the bottoms and inner sides of the trays co-operating with each other to provide a continuous stepped wall subdividing the interior of the casing into an upper display chamber above the trays and a lower storage chamber under the trays.
  2. A braid cabinet including a casing having sides which are inclined upwardly from the front to the rear thereof, the lower portion of the front of the casing having a drawer receiving opening therein, while the back of the casing is provided with an opening, a door normally closing said opening, a removable top normally closing the top of the casing, a thickness of material applied to the inner face of each side of the casing and having the upper edge thereof stepped to provide a series of corresponding tray supporting surfaces having a general inclination corresponding to the inclination of the sides of the casing, a series of removable trays extending transversely across the casing and resting upon corresponding tray supporting surfaces provided by the steps in the thicknesses of material applied to the inner faces of the sides of the casing, said trays being open at the top thereof and the depth of each tray corresponding to the height of the steps so that the trays when assembled have a stepped relation to each other and the bottoms and inner sides of the trays co-operate with each other to provide a continuous stepped wall subdividing the interior of the casing into an upper display chamber above the trays and a lower storage chamber below the trays, the door in the back of the casing opening into the said storage chamber, and a drawer slideable through the drawer receiving opening of the front of the casing.

In testimony whereof we affix our signatures in presence of two witnesses.

JOHN M. BURNHAM.
HERMAN J. SCHNEIDER.
